UNITED STATES PATENT OFFICE.

BERNHART A. BENSON, OF CHICAGO, ILLINOIS, ASSIGNOR TO EDMUNDS & JONES CORPORATION, A CORPORATION OF NEW YORK.

ELECTRIC SWITCH.

Application filed March 29, 1924. Serial No. 702,776.

To all whom it may concern:

Be it known that I, BERNHART A. BENSON, citizen of the United States, residing at Chicago, in the county of Cook and State of Illinois, have invented certain new and useful Improvements in an Electric Switch; and I do hereby declare the following to be a full, clear, and exact description of the invention, such as will enable others skilled in the art to which it appertains to make and use the same.

My invention relates to electric switches of the pull or push type. Generally speaking, the objects of my invention include the providing of a simple, cheaply and easily manufactured switch which will afford self-cleaning contact surfaces, which will permit a considerable continued movement of the switching member in its circuit-closing direction after the circuit is closed, and which will have this switching member spring-retracted so as to open the circuit automatically when the actuating pull or pressure is relaxed. Furthermore, my invention provides a switch construction for this general purpose which will require a minimum of fastening elements.

More particularly, my invention provides a switch construction in which the circuit is closed by the direct contacting of the arms of a resilient switching member with the binding posts of the switch, and one in which these arms are so formed and disposed as to be bent towards each other by engagement with the wire terminals so as to afford a wiping or self-cleaning contact and so as to maintain this contact during a considerable prolonged movement of the switching member. It also provides a novel and simple mounting for the switching member, an effective connection between the circuit-closing portion of this member and a reciprocating plunger, and a cheaply constructed casing assembly which will require no auxiliary fastening elements. Still further and also more detailed objects of my invention will appear from the following specification and from the accompanying drawings, in which—

Fig. 1 is a perspective bottom view of a switch embodying my invention and partic-

ularly adapted for use as a pull switch in connection with the stop-light signal of a vehicle.

Fig. 2 is an enlarged top view of the same switch with the top plate removed and with the switching member in its normal, spring-retracted position.

Fig. 3 is a correspondingly enlarged horizontal section taken along the line 3—3 of Fig. 4.

Fig. 4 is a central, vertical and longitudinal section through the switch, namely a section along the line 4—4 of Fig. 2.

Fig. 5 is a transverse vertical section taken through the binding posts or wire terminals of the switch, or along the line 5—5 of Fig. 2.

Fig. 6 is a section through a portion of the plunger of the switch and through the washer 20 as originally formed, showing a step in the securing of this washer to the plunger.

Fig. 7 is a similar section, showing this washer as flattened and forced into the groove in the plunger.

In the embodiment of the drawings, the switch of my invention comprises a casing having its main body portion composed of a rectangular box provided with extensions forming flanges at the two ends of this body portion of the casing. Such a body portion can readily be formed of sheet metal so as to have a pair of opposed sides 2 formed upwards from the bottom 1, while also having a pair of ends 3 formed upwards and each continued by an end flange 4 having its top flush with the upper edges of the sides 2.

Extending through the bottom 1 of the casing are a pair of binding posts 6 each of which is threaded to receive a screw 7 for securing the end of one of the circuit wires 8 to the same, so that the posts 6 form the effective wire terminals of the switch. Each of the posts 6 has a shank portion extending through a perforation in the bottom 1 of the switch, the perforation in each case being considerably larger than the shank of the post, and the two posts also serve for clamping a pair of insulating blocks 9 and 10 respectively against the lower and upper faces

of the bottom of the casing. For this latter purpose, each post desirably has a contact portion of larger diameter than its shank portion exposed within the casing and beyond the inner insulating block 10, thereby affording a shoulder at the juncture of this larger diametered contact portion with the shank of the post, while the outer end of the post is flared over the exposed face of the insulating block 9 after the manner shown in Fig. 5. Thus arranged, the two posts clamp these insulating blocks tightly to the bottom of the switch casing, thereby preventing the two insulating blocks as well as the posts from moving with respect to the casing. Furthermore, I desirably make the inner insulating block 10 of a size closely approximating the interior width of the casing and desirably have this inner block abut against the nearer end wall 3 of the casing, so as to aid in resisting any sliding tendency which might be due to the thrust of the circuit-closing member.

Extending slidably through alined bores in the ends 3 of the casing is a plunger 11 which forms the actuating member of the switch and which desirably has a head 12 adapted to engage one of the said end walls so as to limit the movement of this stem in the circuit-closing direction. When my appliance is to be used as a pull switch, I desirably provide the other end of the reciprocating plunger 11 with a perforation 13 for receiving a hook end of a spiral end 14 or other connecting link through which the operating pull is transmitted to the sliding plunger of the switch.

The sliding plunger 11 extends through a perforation in an insulating block 15 and the plunger desirably has a larger diametered portion disposed between that block and the head 12 so as to afford a shoulder against which the block 15 is normally pressed by a spring 16. This spring bears at its other end against the opposite head 3 of the switch casing, thereby continuously tending to move both the said insulating block and the plunger in one direction, namely that in which it opens the circuit.

The insulating block 15 desirably is of such a size as to have only a light rubbing engagement with the bottom 1 of the switch casing, whereby this bottom serves to prevent the rectangular block from rocking about the plunger as an axis. Secured to the insulating block 15 is a circuit-closing member which desirably consists of a fork formed of bronze or other resilient metal and having a back portion 17 secured flatwise to the insulator 15 by a rivet 18. Each arm 19 of the said fork has its free end curved towards that of the other arm and the fork member is so formed that its resiliency will normally spread the bent portions of

the free ends of its arm a greater distance apart than the distance between the two binding posts 6 which form the terminals of the switch. Moreover, these arm tips are spaced lengthwise of the switch from both posts when the plunger is in its spring-retracted position of Figs. 2 and 4, thereby normally keeping the circuit open between the terminals 6.

When the plunger is moved in a direction which is towards the left in Figs. 2 and 4, either by pressing the head 12 or by pulling on the link 14, the bent tips of the fork arms 19 respectively engage the two posts 6 after a predetermined movement of the plunger in the said direction, as shown in dotted lines in Fig. 3. Then a continued movement of the plunger in the same direction will cause the curved surfaces of the posts 6 and the bent tips of the said arms to cooperate in affording a cam action so as to force the arms towards each other. Consequently, these arms will continue to contact respectively with the two posts during a considerable range of movement of the actuating plunger as indicated by the full lines in Fig. 3, which lines show the plunger as stopped at the limit of its circuit-closing movement by the engagement of the head 12 of the plunger with the adjacent end wall 3 of the casing. Owing to the wiping action thus secured, the switch of my invention is self-cleaning and will automatically clear itself of any dust which may have settled on the terminal posts or on the resilient switching member. So also, the contacting of the arms of the switching fork with the said terminals during a prolonged movement of the switching member adapts my switch to purposes where the extent of movement of the actuating member may vary considerably, as for example in the stop-light switches of automobiles which are commonly connected to the brake levers for their actuation. To prevent the plunger from being withdrawn from the casing towards this head end, I provide this with an enlargement adapted to engage the inner face of the casing end which is adjacent to the head of the plunger, as shown by the head 20 of Fig. 4.

It will be obvious from the above that the switch of my invention is exceedingly simple and inexpensive in construction, that it requires very few fastening elements in its construction and that the contact arrangement permits the resiliency of the forked switching element to compensate for any irregularities in the exact size or assembly of the parts. Moreover, since this forked metal element is entirely disconnected from the circuit when in its normal retracted position, it is immaterial whether or not the rivet 18 touches the adjacent end wall of the casing at that time, or whether it is held away

from the casing by the interposing of the bead 20 between that wall and the insulating block 8 of the switching member.

However, while I have illustrated and described the switch of my invention in an embodiment including numerous highly desirable details of construction and arrangement, I do not wish to be limited to these, as many changes might obviously be made without departing either from the spirit of my invention or from the appended claims.

For example, I am here showing the plunger or actuating element of the switch as provided with a bead 20 which limits the movements of the insulator along the plunger in one direction and which also engages one end wall of the switch casing to limit the movement of the plunger in the same direction. To permit a ready assembling of switch parts including such a construction, I provide this bead in the form of a thin washer which is initially of a frusto-conical shape as shown in Fig. 6, and provide the plunger with a peripheral groove (also shown in the same figure) of a width corresponding to the thickness of the washer. In assembling the parts, the plunger is slid through the end wall which is nearest the head of the plunger in the assembled switch, and successively through the washer 20, the insulator 15 and the spring. I then force the spring away from the insulator and flatten the washer so as to cause it to enter the groove in the plunger, thereby anchoring the washer to the plunger as shown in Fig. 7 and causing this effectively to form a laterally projecting bead on the plunger. I also desirably increase the diameter of the plunger in the portion between this groove and the head of the plunger, so as to afford a greater thrust bearing against the washer in the direction in which the thrust is exerted during the circuit-closing movement of the plunger.

I claim as my invention:—

1. An electric switch comprising a casing, a reciprocable plunger mounted therein, a pair of wire terminals disposed at opposite sides of the plunger, an insulator disposed in the casing and having the plunger extending through the same, the plunger having means engaged by the casing to limit the movement of the plunger in one direction and also having means engaged by the insulator to limit the movement of the insulator along the plunger in the same direction, spring means interposed between the insulator and the casing to urge the insulator in the said direction, and a contact member mounted on the insulator and adapted to contact with both wire terminals when the insulator is moved in the opposite direction against the resistance of the spring.

2. A switch as per claim 1, including a

washer fastened to the plunger and disposed between the insulator and a wall of the casing and affording both of the said limiting means.

3. A switch as per claim 1, in which the plunger has a peripheral groove disposed between the insulator and a wall of the casing, in combination with a washer having its radially inner portion disposed in the said groove, the washer affording both of the said movement limiting means.

4. In an electric switch, a casing having a pair of end walls each provided with a perforation, a plunger extending through the said perforations and having an enlargement normally engaging the inner face of one of the said end walls to limit the movement of the plunger in one direction, an insulator mounted on the plunger, a spring continuously pressing the insulator against the said enlargement and thereby holding the enlargement against the said one of the end walls and resisting a movement of the plunger in the opposite direction, a contact member on the insulator, and a circuit terminal mounted in the casing and engaged by the contact member when the plunger and the insulator are moved in the last named direction, the plunger having a head disposed outside the casing and adapted to engage the said one end wall to limit the movement of the plunger in the direction in which it causes the contact member to engage the circuit terminal.

5. In an electric switch, a casing having a pair of end walls each provided with a perforation, a plunger extending through the said perforations and having an enlargement normally engaging the inner face of one of the said end walls to limit the movement of the plunger in one direction, an insulator mounted on the plunger, a spring continuously pressing the insulator against the said enlargement and thereby holding the enlargement against the said one of the end walls and resisting a movement of the plunger in the opposite direction, a contact member on the insulator, and a circuit terminal mounted in the casing and engaged by the contact member when the plunger and the insulator are moved in the last named direction, the insulator having a wall slidably engaging a wall of the casing to prevent the insulator from rotating about the plunger.

6. In an electric switch, a casing having a pair of end walls each provided with a perforation, a plunger extending through the said perforations and having an enlargement normally engaging the inner face of one of the said end walls to limit the movement of the plunger in one direction, an insulator slidably mounted on the plunger, a spring continuously pressing the insulator against the said enlargement and

thereby holding the enlargement against the said one of the end walls and resisting a movement of the plunger in the opposite direction, a contact member mounted on the 5 insulator, and a pair of relatively insulated circuit terminals mounted in the casing and both engaged by the contact member when the plunger and the insulator are moved in the last named direction against the resistance 10 of the spring.

7. In an electric switch, a casing having a pair of end walls each provided with a perforation, a plunger extending through the said perforations and having an enlargement 15 normally engaging the inner face of one of the said end walls to limit the movement of the plunger in one direction, an insulator mounted on the plunger, a spring continuously pressing the insulator 20 against the said enlargement and thereby holding the enlargement against the said one of the end walls and resisting a movement of the plunger in the opposite direction, a contact member mounted on the insulator, 25 and a pair of relatively insulated circuit terminals mounted in the casing and both engaged by the contact member when the plunger and the insulator are moved in the last named direction against the resistance 30 of the spring, the contact member having a pair of arms extending in the said one di-

rection, the arms having their free end portions bowed toward each other and having the bends of their said bowed portions normally spaced farther apart than the circuit 35 terminals.

8. An electric switch comprising a casing, a plunger extending slidably through the casing, an insulator carried by the plunger, a resilient and substantially U-shaped contact member having its back fastened to the insulator and having arms extending in the same general direction with the plunger and bowed towards each other, a pair of circuit terminals respectively disposed in the path of the said arms and spaced so as to flex the arms toward each other when the plunger is moved so as to carry the insulator and the contact member toward the circuit terminals, a spring continuously urging the plunger in the opposite direction, and means for limiting the movement of the plunger by the spring. 40

9. An electric switch as per claim 8, in which the insulator has a perforation 45 through which the plunger extends and has a portion slidably engaging a wall of the casing to prevent the insulator from rotating about the plunger. 50
